[57] CLAIM

The design for an ornamental rescue bed insert, as shown and described.

DESCRIPTION

FIG. 1 is a perspective view of a rescue bed insert showing my new design;
FIG. 2 is a front plan view showing an open configuration thereof;
FIG. 3 is a perspective view of the open configuration of FIG. 2;
FIG. 4 is a rear view of the open configuration of FIG. 2;
FIG. 5 is a top elevational view thereof;
FIG. 6 is a side elevational view thereof;
FIG. 7 is a perspective view showing a folded configuration thereof; and,
FIG. 8 is a front elevational view thereof.
The broken line illustration of human and stretcher are for illustrative purposes only and form no part of the claim design.
